UNITED STATES PATENT OFFICE.

GEORGE J. HATZ, OF BLOOMINGTON, ILLINOIS.

LOCOMOTIVE EXHAUST MECHANISM.

No. 832,858

Specification of Letters Patent.

Patented Oct. 9, 1906.

Application filed February 23, 1906. Serial No. 302,514.

To all whom it may concern:

Be it known that I, GEORGE J. HATZ, a citizen of the United States, residing at Bloomington, in the county of McLean and State of Illinois, have invented certain new and useful Improvements in Locomotive Exhaust Mechanism, of which the following is a specification.

The invention relates particularly to a steam-locomotive which is provided with the usual smoke box and stack at the front end, and especially to the arrangement for accelerating the draft through such parts, all of which will more fully hereinafter appear.

The principal object of the invention is to provide simple, economical, and efficient means for accelerating the draft of a steam-locomotive.

The invention consists in the features, combinations, and details of construction hereinafter described and claimed.

In the accompanying drawings, Figure 1 is a longitudinal sectional elevation of the front end of a locomotive-boiler, taken on the line 1 of Fig. 2 looking in the direction of the arrow, showing the parts as they appear when constructed and arranged in accordance with these improvements; Fig. 2, a cross-sectional elevation taken on the irregular line 2 of Fig. 1 looking in the direction of the arrow, a portion of the stack and extension being also shown in section; Fig. 3, a plan sectional detail taken on line 3 of Fig. 2 looking in the direction of the arrow; Fig. 4, a plan view of the steam-jet ring looking at it from above; Fig. 5, a front end elevation of a locomotive embodying these improvements; and Fig. 6, a side elevation of a portion of the front end of the locomotive shown in Fig. 5.

In constructing a locomotive in accordance with these improvements a boiler portion *a* is provided having the usual flues *b* extending therethrough to the flue-sheet *c* at the front end of the locomotive. The front end of the locomotive-boiler is provided with the usual smoke-box *d*, formed by the forward cylindrical extension *e* thereof, as shown particularly in Figs. 1 and 6.

It is very desirable to provide convenient and efficient means for accelerating the draft of the locomotive and to so arrange the mechanism that a minimum amount of fuel in the fire-box may be consumed while the engine is at a standstill, and yet keep the fire from going out. To accomplish this, the usual stack portion *f* is provided and secured

to the cylindrical extension *e* of the locomotive in the usual manner and directly over and in line with the usual exhaust-nozzle *g*. As is well known in such instances, the exhaust-nozzle *g* is connected with the exhaust of the engine-cylinders *g'* and *g''* in the usual manner, so that when the locomotive is running the exhaust-steam therefrom is forced through the smoke-stack, and thereby increases the draft in the fire-box, all of which is well known and understood by those skilled in the art. To increase this feature of the locomotive and at the same time minimize the danger of live sparks passing out of the locomotive, as well as to maintain the fire in the fuel-chamber while the engine is at a standstill, I provide what I prefer to term a "secondary" stack *h* and nest it inside of the main stack and concentric therewith, as shown particularly in Figs. 1 and 2. The bottom portion of this secondary stack is provided with a flaring portion *h'*, and a depending "petticoat" portion *i*, extending into the smoke-box, as shown particularly in Figs. 1 and 2, and forming a practical continuation of the main stack, is also provided. The main and secondary smoke-stacks are secured together by means of a plurality of partitions *j*, (see Fig. 3,) extending vertically between the same, so as to form four vertical chambers *k* therebetween—that is, what would otherwise be an unbroken annular chamber is divided into four draft-compartments.

Arranged beneath the petticoat of the main stack is what I prefer to term a "fluid-pressure" jet-ring *l*, formed of a hollow annulus or ring portion having an annular chamber *m*. The lower portion of this ring is imperforate, while the upper portion, as shown particularly in Fig. 4, is provided with a plurality of nozzles or perforations *n*, arranged under and directly in line with the "draft-compartments" *k*, as I prefer to term them. This steam-jet ring is connected, by means of the pipes *p* and *p'* preferably, with the live-steam channel of the locomotive, though it can be connected with the exhaust-steam channel as well. The connections with the steam-channel by these pipes *p* and *p'* are not shown; but it can be determined from an inspection of Fig. 5 that the pipes are continued through the walls of the engine-frame and meet with the steam-channel, as suggested above.

From the foregoing description of con-

100 Note

110

struction and arrangement it will be seen that when the engine is going a continuous draft is forced through these draft-compartments, which assists in carrying out with it a 5 larger portion of the spent gases and products of combustion, thereby accelerating in an efficient manner the draft in the fire-box. At the same time it will be understood that this is an additional means to the artificial 10 draft created by the usual exhaust-nozzle *g*.

The advantage of the present construction is that the exhaust-nozzles contained therein can be at least thirty per cent. larger than the exhaust-nozzles in the usual constructions, thereby relieving back pressure in the cylinder during the running of the locomotive, saving wear and tear on the machinery, and making the engine ride much better. It 15 will also be seen that the locomotive engineer 20 has at his disposal the equalizing of the draft through the smoke-stack, so that the fuel consumption is perfected thereby and a better or more perfect combustion takes place when the engine is in operation.

Continuing the description of the construction shown in the figures, a third detached intermediate pipe *q* is provided and arranged in line with the axis of the secondary stack directly underneath its hood and between it 30 and the opening in the exhaust-nozzle *g*. It will be seen, therefore, that there are three openings through which exhaust steam, gases, and products of combustion may find a passage from the smoke-box to the outer air—that is, through and under the hood *g'* or intermediate stack, through and under the hood *h'* of the secondary stack, and through and under the hood portion of the petticoat *i*. 35

To further assist in the operations of the 40 engine, a steam-supply pipe *r* is provided and connected with a source of live-steam supply, preferably the dome portion. (Not shown.) This steam-supply pipe *r* may be provided with a valve that can be operated from the engine-cab, so that when the engine 45 is standing still or even when it is running the engineer can furnish a supply of steam under pressure to the intermediate detached stack or pipe portion and maintain a mini- 50 mum draft—that is, maintain a minimum draft when the engine is standing still and increase the draft when it is running. These supply-pipes—one for live steam *r* and those for the exhaust-steam *p* and *p'*—are provided 55 with check-valves *s*, *s'*, and *t* to prevent the return flow of pressure. An inspection of Fig. 6 will show that live steam may be fed through pipe *r*, which is also connected by means of a branch pipe *r'* with the pipe *p'*, 60 where the check-valve *t* prevents steam from passing from the pipe *p'* to the pipe *r*. By this arrangement it will be seen that live steam when desired can be fed not only to the intermediate detached stack *g*, but also 65 to the steam-jet ring *m* to assist in the draft

when the engine is standing still, all of which will be understood and appreciated by those skilled in the art.

It is believed that an engine equipped with these improvements will not only have a better draft while the locomotive is in operation and when at a standstill, but that, as already suggested, it will ride better on account of the increase in size of the main exhaust-nozzle. Further, an engine equipped with this invention 75 can use a poorer grade of coal further without forming any clinkers to speak of, and, finally, the cleaning of the front end also prevents the boiler from getting hot and cracking, which is quite an item of expense to the 80 large railroads, in that the boiler-fronts have to be frequently renewed on this account.

The draft-chamber, as shown in Fig. 1, is provided with a piece of wire mesh *u*, arranged, as shown, in combination with an 85 imperforate baffling-plate or apron *w*, forming therewith a substantial U-shaped portion, one wall of which is imperforate. Arranged at the front box of this U-shaped portion of reticulated material, as shown in Fig. 90 1, is a perforated diaphragm *x*, that prevents the piling up of the sparks and ashes in front thereof. This perforate diaphragm is placed in an unusual position in a locomotive constructed in accordance with these improvements. Usually it is rear of the exhaust-nozzle; but I have found it the better practice in this type of construction to place it as shown in Fig. 1.

I claim—

1. In a locomotive of the class described, the combination of a boiler portion provided with a smoke-box at the front end, a main-stack portion arranged over the usual smoke-box, a secondary stack concentrically nested 105 therein and providing one or more draft-compartments therebetween, and means for introducing steam or other fluid under pressure through such draft-compartments, substantially as described.

2. In a locomotive of the class described, the combination of a boiler portion provided with the usual smoke-box at the front end, a main-stack portion secured to the locomotive above the smoke-box, a secondary stack 115 concentrically nested therein extending down into the smoke-box and providing one or more draft-compartments therebetween, a petticoat portion forming a continuation of the main-stack portion surrounding the secondary-stack portion in the part thereof located in the smoke-box, and a hollow ring or annulus connected with a source of steam-supply for forcing a supply of steam or other fluid under pressure through the draft-compartments between the main and secondary stacks, substantially as described.

3. In a locomotive of the class described, the combination of a boiler portion provided with the usual smoke-box at the front end, a 125

main-stack portion secured to the smoke-box and extending upwardly therefrom, a secondary stack concentrically nested therein and extending down into the smoke-box and provided with a flaring portion at its lower end forming one or more draft-compartments between it and the main stack, a petticoat portion depending into the smoke-box forming a continuation of the main stack and provided with a flaring portion at its lower end, a hollow ring or annulus encircling the secondary-stack portion under the petticoat portion and provided with one or more openings through its upper surface for introducing a supply of steam into and through the draft-compartments between the main and secondary stacks, and pipe mechanism connecting the hollow ring or annulus with a source of steam-supply, substantially as described.

4. In a locomotive of the class described, the combination of a boiler portion provided with the usual smoke-box at the front end, a main-stack portion secured to the smoke-box and extending upwardly therefrom, a secondary stack concentrically nested therein and extending down into the smoke-box and provided with a flaring portion at its lower end forming one or more draft-compartments between it and the main stack, a petticoat portion depending into the smoke-box forming a continuation of the main stack and provided with a flaring portion at its lower end, a hollow ring or annulus encircling the secondary-stack portion under the petticoat portion and provided with one or more openings through its upper surface for introducing a supply of steam into and through the draft-compartments between the main and secondary stacks, pipe mechanism connecting the hollow ring or annulus with a source of steam-supply, a main exhaust-nozzle connected with the locomotive-engine cylinders arranged underneath and in line with the axial center of the main and secondary stacks, and

an intermediate stack or pipe portion *q* arranged between the opening of the exhaust-nozzle and the secondary stack, substantially as described.

5. In a locomotive of the class described, the combination of a boiler portion provided with a smoke-box at its forward end, a main-stack portion secured thereto and extending upward therefrom directly above the smoke-box, a secondary-stack portion concentrically nested therein and extending from end to end of the main-stack portion provided with a flaring portion at its lower end and forming one or more draft-compartments therebetween, a petticoat portion depending into the smoke-box and forming a continuation of the main stack and provided with a flaring portion at its lower end, a main exhaust-nozzle located at the lower portion of the smoke-box in line with the axial center of the secondary stack and connected with the exhaust of the locomotive-engine cylinders, an intermediate stack or pipe portion provided with a lower flaring portion arranged between the main exhaust-nozzle and the secondary-stack portion, a hollow steam-jet ring or annulus surrounding the secondary-stack portion and provided with a plurality of nozzles or openings in line with the draft-compartments between the main and secondary stacks, pipe mechanism connecting this steam-jet ring with the steam-channel of the locomotive-engine cylinders, a second pipe *r* connected with a source of live-steam supply and having its main opening arranged in the intermediate stack or pipe, and a branch pipe *r'* connecting the pipe *r* with the pipes leading to the exhaust and steam jet ring, substantially as and for the purposes described.
